UNITED STATES PATENT OFFICE.

ERNEST J. W. MULLER, OF NEW YORK, N. Y., ASSIGNOR TO AMERICAN BANK NOTE COMPANY, A CORPORATION OF NEW YORK.

ROTARY MULTICOLOR-PRINTING MACHINE.

1,170,841.

Specification of Letters Patent. Patented Feb. 8, 1916.

Application filed June 7, 1913. Serial No. 772,227.

To all whom it may concern:

Be it known that I, ERNEST J. W. MULLER, a citizen of the United States, residing at the borough of Brooklyn, in the city of New York, county of Kings, and State of New York, have invented certain new and useful Improvements in Rotary Multicolor-Printing Machines, of which the following is a specification, reference being had therein to the accompanying drawings, which form a part thereof.

My invention relates to rotary multi-color printing machines, and more particularly to that type thereof known as photogravure presses.

In the printing art, photogravure presses differ from all other types of presses in certain essentials, and in order that my invention may be more readily understood, I will describe briefly the more important distinctions between photogravure work and other printing methods.

The plate used upon a photogravure press is an intaglio plate, usually an acid-etched copper plate, and the ink is applied to this plate by a single roller, immersed in fluid ink contained in the font. The font, the inking roller and the form surface are all heated to maintain fluidity of the ink, 25 plus ink being removed from the top or non-printing portion of the plate surface by a scraper or doctor bar. The ink used has a waxy vehicle so as to be extremely quick 30 drying, and the impression is made upon a dry sheet of paper. Hence it will be seen that photogravure work is similar to steel plate printing, differing therefrom, however, in the manner of applying the ink, in the manner of cleaning the non-printing 35 surface and in the character of the ink used.

There is the further difference that in steel plate engraving, the paper upon which the impression is made is previously dampened. There are other and minor differences 40 not necessary to refer to herein.

Heretofore, in photogravure work, it has been impossible to produce a multi-color design in which the different colors are in register with a single feeding operation, particularly in view of the fact that offset printing is not applicable to this class of work because of the quick drying properties of the ink used.

With these conditions in mind, the main 55 object of my invention is to provide a rotary printing press especially adapted for

photogravure work, wherein a multi-color imprint may be made with a single run of the press, the different portions of the design of different colors being in register 60 upon the printed sheet.

A further object is to provide a press of this character wherein registering impressions in different colors will be successively made without likelihood of smutting or defacing the colors first applied, thus insuring perfect register or a clean line of demarcation between different colors entering 65 into a design.

A still further object is to provide a press 70 of this character wherein the several color impressions may be made by a continuous operation of the machine, thus insuring perfect register and increased capacity.

A still further object is to provide a press 75 of this character embodying therein a printing mechanism consisting of a single impression cylinder and a plurality of plate or form cylinders, each having an independent inking mechanism, wherein said impression 80 cylinder and said form or plate cylinders may be simultaneously thrown out of the printing relation without disturbing the relation of each plate or form cylinder and its inking mechanism.

A still further object is to provide a press 85 of this character wherein the ink fonts and rollers may be removed from the machine independently of each other, and of the scraper or doctor bar.

A still further object is to provide in a machine of this character, means disposed between succeeding plate or form cylinders, whereby a sheet of paper passing through the press will have the ink thereon thoroughly dried prior to the succeeding impression, thus avoiding smutting or smearing of each preceding impression and permitting a perfect register of the different colors, and the use of plates upon succeeding plate 95 or form cylinders, of the same dimensions, as well as the dispersion of different colors throughout the design when desired. And a still further object is to provide a printing machine of this character wherein the operation of parts may be synchronized, and the plate or form cylinders may be so adjusted as to secure an imprint in different colors in register with each other.

The invention consists primarily in a rotary multi-color printing machine embodying 110 therein a sequence of form or plate cyl-

inders, an inking mechanism adapted to co-
operate with the plates upon each of said
cylinders, an impression surface for each of
said cylinders, and means intermediate suc-
ceeding cylinders whereby the ink upon the
paper will be dried while passing from one
cylinder to the other; and in such other
novel features of construction and combi-
nation of parts as are hereinafter set forth
10 and described, and more particularly
pointed out in the claims hereto appended.

Referring to the drawings:—Figure 1 is
an elevation of one side of a press embody-
ing my invention; Fig. 2 is an elevation of
15 the other side of said press; Fig. 3 is an
elevation of the delivery end of the press;
Fig. 4 is detail view of the ink fonts and
the parts appurtenant thereto; and Fig. 5
is a detail view of the mechanism for throw-
20 ing the impression cylinder and the form
or plate cylinders out of the operative rela-
tion.

Like letters refer to like parts throughout
the several views.

25 In the accompanying drawings, I have
shown only the printing mechanism and the
parts appurtenant thereto, omitting the
feeding and delivery mechanisms, any type
of which may be used in connection with
30 my invention.

In the drawings, I have shown a type of
press adapted to be used in connection with
a continuous paper web, although single
35 sheets of paper may be used by adapting to
my invention a feed and delivery mechanism
capable of handling single sheets.

40 In the form of my invention shown in
the drawings, 1 indicates the frame of the
machine, 2 the main power shaft, and 3 the
gear train connecting said power shaft with
the main gear 4, for actuating the printing
mechanism.

45 Mounted in the frame 1 is an ordinary
blanketed impression roller 5, carried by the
same shaft as the gear 4. Grouped about
the cylinder 5 is a plurality of plate or form
cylinders 6, 7, the ends of which have
50 mounted thereron the gears 8 and 9 respec-
tively, meshing with the gear 4 so as to
cause said plate or form cylinders to be
rotated at the same peripheral velocity as
the cylinder 5. To permit the circumfer-
55 ential adjustment of the cylinders 6 and 7,
for the purpose of securing the proper regis-
ter, I provide the gears 8 9 with segmental
slots as shown in Fig. 2, said gears being
secured to their respective cylinders by
means of bolts for the purpose of facilitat-
ing this adjustment.

60 Each of the cylinders 6, 7 is mounted in
bearings adjustable toward and from the
axis of the impression cylinder 5, and ad-
justment screws 10, 11, acting upon each
bearing are provided so as to permit the set-
65 ting of these cylinders in a manner to se-

cure the requisite pressure between the cyl-
inder or plate thereon and the impression
roller.

Each of the cylinders 6 and 7 is provided
with a heating device interiorly thereof,
common in this and analogous types of ma-
chines. In the machine shown in the draw-
ings, I contemplate the use of an electrical
resistance heater, drawing its current from
the disk contact 12, 13, carried by said cyl-
inders respectively, and the opposed con-
tacts, 14 and 15, connected with the con-
ductor 16 17 leading to any desired source of
electrical supply.

The shaft of the cylinder 5 is mounted in
the eccentric bushings 18 19, which in turn
are mounted in housings 20, 21, means be-
ing provided in connection with said eccen-
tric bushings for raising or lowering the
impression cylinder for the purpose of
throwing it out of the operative relation
with all of the plate or form cylinders si-
multaneously.

Each of the eccentric bushings 18 19 is
provided with a crank 22, 23, which cranks
are connected by the adjustable links 24 25
to the cranks 26 27, upon the shaft 28, hav-
ing secured thereto an elongated handle 29.
By this construction I am enabled to throw
the impression cylinder out of the operative
relation to the plate or form cylinders,
when desired, and to throw it into the op-
erative relation in a manner to develop the
requisite high pressure between the plate or
form and the impression cylinder.

Associated with each of the cylinders 6, 7,
is an inking roller 30 31 adapted to be par-
tially submerged in the ink contained in the
font 32, 33, respectively, and to apply ink
therefrom to the plates or cylinders upon
said cylinders 6, 7. Beyond these inking
rollers 30, 31 respectively are the scrapers
or doctor bars 34, 35, which project at an
angle toward and bear upon the plates or
cylinders upon the cylinders 6, 7, in the gen-
eral direction of the direction of rotation
of these cylinders.

The scrapers or bars 34, 35 are mounted
in adjustable heads 36, 37, carried by lat-
erally reciprocatable slides 38, 39. The lat-
eral movement of the scrapers or bars dis-
tributes the wear thereon and removes ink
from the top or non-printing surface of the
cylinders in a manner to prevent streaking.

The heads 36, 37 are pivotally mounted
upon the slides 38, 39, and are set so as to
secure the desired intimate relation between
the bars 34, 35, and the plates or cylinders
upon the cylinders 6, 7, by means of the ad-
justment screws 40, 41.

Upon one side of the machine is a shaft
42, driven from the main power shaft 2 by
the shaft 43 and beveled gears 44, 45, 46 and
47. Mounted upon the shaft 42 are the ec-
centrics 48 and 49, inclosed by the straps 50

1

10

11

12

13

14

15

and 51, which straps are connected respectively by pivoted links as 52 with the slides 38 and 39. By this construction, both of the slides are continuously reciprocated 5 while the press is running.

When only two form or plate cylinders are used, the construction heretofore described and shown in the drawings may be used to advantage, but if the number of 10 form or plate cylinders be increased, independent means for actuating said slides might be required.

The font 33 is mounted upon slides on the frame 1, and acting upon said font are the 15 set screws 53, 54, mounted in arms 55, 56, carried upon the rod 57. The arms 55, 56, are adapted to be locked upon said rod 57 by means of the set screws 58 and 59, a construction which permits said arms when released from said rod to be dropped to afford a clearance for the removal of said font. The use of movable and adjustable means for positioning the font 33 is made necessary because of the fact that the doctor bar 20 35 overhangs and projects within said font and some such construction is necessary to permit the handling of said font in a manner to permit its withdrawal past the doctor bar.

30 The font 32 is located upon supports between the slides 38, 39, and its inking roller 30 is located inside of the vertical diameter of the plate or form cylinder 6. This construction necessitates supporting means for 35 said font 32 so constructed and arranged as to permit this font to be dropped when removing it from the machine to a point where it may pass below the slide 38 and permit the inking roller 30 thereof to clear the cylinder 6. This supporting means comprises the 40 pivoted angle arms 60, 61, the long arms of which are adapted to engage the bottom of the font 32 adjacent the outer end thereof, and the short arms of which are adapted to 45 engage the adjustable stop screws 62 and 63 carried upon the swivels 64 and 65. By this construction, the font 32 and its inking roller 30 may be raised by means of the adjustable stops 62 and 63 to develop the desired pressure of the inking roller upon the 50 plate or cylinder upon the form or plate cylinder 6, and the support for the outer end thereof may be removed at any time by turning the swivels 64 and 65, thus permitting the entire font to be dropped within the 55 frame 1 and removed from the machine.

The manner of mounting the ink fonts and their appurtenances is necessitated by structural difficulties encountered in grouping a plurality of printing cylinders and the inking mechanisms appurtenant thereto about a single impression cylinder. The actual inking mechanism employed is substantially like the inking mechanism common to photogravure presses, and no claims

for said inking mechanism *per se* are made herein.

While the inks used in photogravure work are quick drying, fairly hard inks, the difficulty encountered in producing a photogravure press capable of producing multi-color work has been that the ink does not dry sufficiently rapidly under normal conditions to permit successive impressions in different colors to be taken. With a high 75 speed press, and in this sense the term high speed is used merely comparatively, as the speed of a photogravure press is always low compared to that of a high speed type printing press, the elapsed time between impressions is very slight. To obviate this difficulty, I provide means between succeeding plate or form cylinders whereby the paper in passing from one cylinder to the other is acted on in a manner to thoroughly set 80 the ink after each impression has been taken. This means comprises, in the form of the invention shown, a plurality of nozzles extending axially of the impression cylinder and directed theretoward, whereby 85 air, which may be chilled, is continuously projected upon the printed surface of the paper, thus expediting the setting or drying process of the ink so that before it passes to the next plate or form cylinder the ink will 90 be thoroughly dried, thus permitting the taking of a second impression without likelihood of smearing or smutting the first impression. In the accompanying drawings, 95 these means for setting or drying the ink between impressions comprise an airline 66, leading to the distributing tubes 67 having a plurality of reduced openings therein. This distributing tube is positioned in close juxtaposition to the surface of the impression cylinder 5, so that the air delivered toward said cylinder will be diffused in a manner to act upon the entire surface of the 100 paper between the cylinders 6 and 7.

Carried by the frame 1, above the impression roller 5 are guide rollers 68, 69, 70 and 71, about which a paper web is adapted to be threaded in feeding it to and delivering it from the delivering mechanism. One of these rollers as 70 is loosely mounted upon 105 the shaft 28.

The operation of the herein described machine is substantially as follows:—The font 33 is mounted upon its slides and brought into position with the ink roller 31 engaging 110 the plate or cylinder upon the cylinder 7, the arms 55 and 56 are raised until the screws 53 and 54 engage the end wall of said font, and the set screws 58 and 59 then set upon the rod 57, to hold said arms in position. The screws 53 and 54 may then be adjusted to properly position the font and the ink roller. The inner end of the font 32 is 115 then placed upon its slides with the outer end thereof lowered, and the outer end sub- 120 125 130

4

sequently raised within the doctor bar slide 38. The arms 60 and 61 are then swung so as to engage the bottom of said font, the swivels 64 and 65 being used to bring the stop screws 62 and 63 into engagement with the short arms of said levers. These stop screws, 62 and 63, may be adjusted to raise or lower the font 32 slightly to bring the inking roller 30 into the proper position 5 relative to the plates or cylinders upon the cylinder 6. The fonts may be removed by reversing these operations. The machine is now in condition for operation, and a web is threaded therethrough, or sheets are fed 10 thereto, in any desired manner. The eccentric bushings 18 and 19 are then rotated by means of the handle 29, shaft 28, cranks 26 and 27, links 24 and 25 and cranks 22 and 23, forcing the impression cylinder 5 down- 15 wardly and developing the requisite pressure between said cylinder and the plates or cylinders on the form or plate cylinders 6 and 7. When power is applied to the machine, the impression cylinder 5, will 20 through its gear 4 be rotated, the cylinders 6 and 7 being rotated at the same peripheral velocity by the gears 8 and 9 carried thereby and in mesh with the gear 4. As the rollers 6 and 7 are rotated, they will, 25 through frictional engagement, rotate the inking rollers 30 and 31, respectively, causing said rollers to deposit upon the surface, and force into the intaglio lines, of the printing plate or cylinder, ink of the different colors carried in the respective fonts 32 and 33. The doctor bars or scrapers 34 and 35 bearing upon the surface of the plates or cylinders upon the cylinders 6 and 7, respectively, will remove the ink from the 30 non-printing or top surface of the plates or cylinders, the lateral reciprocatory movement of said scrapers or bars preventing unequal wear of these scrapers or bars and a resultant streaking of the plate. The ink re- 35 moved from the top or non-printing surface of the plate or cylinder will be restored to the fonts 32 and 33 respectively. As the portion of the plate or cylinder upon the plate or form cylinder 6 reaches the print- 40 ing position, it will impress the intaglio design therein upon the paper in one color, and the paper will then pass to the cylinder 7, the plate or cylinder upon which has been inked in the same manner as the plate or 45 cylinder upon the cylinder 6, and the paper will receive another impression in accordance with the design upon the plate or cylinder thereon, but in a different color. While the paper is passing from one cylinder to 50 the other, it will be continuously subjected to the action of the air jets from the tube 67, so that before the impression is made in one color, the ink of the preceding color will be thoroughly dried or set upon the paper. If 55 it be found that the different colors do not

register, either cylinder 6 or 7 may be adjusted circumferentially by releasing the bolts attaching them to the gear 8 or 9. It will thus be observed that by running the paper once through the machine, a multi- 70 color impression may be secured, and that different colors may be caused to have perfect register. Furthermore, the drying or setting of the ink of one impression before making a subsequent impression in a differ- 75 ently colored ink, will prevent smutting or smearing of preceding impressions by the non-printing surface of succeeding printing plates or cylinders.

If desired, one color may be partially su- 80 perimposed upon another, although this is not as a rule desirable, nor necessary, as perfect register can be secured and transparent colors are not adapted for use in photogra- 85

The impression cylinder 5 may be thrown out of the printing relation to the plate or form cylinder 6 or 7 by means of the mecha- 90 nism controlled by the handle 29.

The adjustment screws 10 and 11 may be 90 used to bring the cylinders 6 and 7 into the desired operative relation to the impression cylinder 5 or either of these screws may be used to throw either cylinder out of the 95 printing relation thereto so as to permit the machine to be run upon a single color.

Throughout the specification I have used the term "plate or cylinder carried by the cylinders 6 or 7" and in so doing have referred to the common practice of using 100 continuous copper cylinders bearing the intaglio design commonly used in photogravure work, and to ordinary, semi-cylindrical etched plates bearing the intaglio design, which may be substituted 105 therefor.

I believe it to be broadly new in a photogravure printing machine to provide a sequence of plate or form cylinders each having associated therewith a suitable inking mechanism, which cylinders are adapted to make successive impressions in different colors while paper is running once through the machine, and furthermore, to provide means intermediate the succeeding 115 printing cylinders for setting or drying the ink upon the paper after the making of one impression and before the making of a succeeding impression.

It is not my intention to limit myself to the precise details of construction shown in the accompanying drawings, it being apparent that such may be varied without departing from the spirit and scope of the invention.

Having described my invention, what I claim as new and desire to have protected by Letters Patent, is:

1. A rotary multi-color printing machine embodying therein a main frame, an im- 13

- 5 pression cylinder mounted therein, a plurality of form cylinders mounted in said frame below the impression cylinder, a laterally reciprocatory doctor bar mounted
10 in said frame adjacent and bearing upon the plates on each of said form cylinders, a removable ink-font slidable upon said frame toward and into engagement with the plates on one of said form cylinders,
15 means securing said font in position relative to said cylinder, an ink roller carried by said font, an ink-font associated with the other form cylinder, supports therefor intermediate said doctor bars, an ink roller
20 carried by said font, adjustable means whereby one end of said font will be supported and may be raised or lowered to develop the requisite pressure between the said inking roller and the plates on said cylinder and said font and said inking roller may be dropped below said form cylinder and the doctor bar associated therewith to permit the withdrawal and removal of said font and its roller, and
25 5 means for projecting a setting medium toward said impression cylinder intermediate said form cylinders.
2. A rotary multi-color printing machine embodying therein a sequence of form or plate cylinders, an ink font for each of said form or plate cylinders, an inking roller for each said font adapted to apply ink therefrom directly to the plate or cylinder upon its plate or form cylinder, a
30 5 doctor bar or scraper for each said font
35 adapted to remove ink from the top or non-printing surface of said plate or cylinder and return it to said font, whereby a plurality of impressions in different colors may be consecutively made upon a single run of 40 the paper through the machine, one of said fonts being arranged between said doctor bars or scrapers, one end of said font being supported by the frame of the machine and the other end thereof being supported by a 45 plurality of oscillatory levers, one arm of which respectively engages the bottom of said font, and the other arm of which is adapted to be engaged by an adjustable stop, and supports for said stops whereby 50 said levers may be oscillated to permit the end of said font to be dropped beneath one of said doctor bars or scrapers, and the inking roller carried by said font may be moved toward or from its plate or form 55 cylinder, an impression surface for each of said cylinders, and means intermediate succeeding cylinders whereby the ink upon the paper will be dried or set while passing from one cylinder to the succeeding cylinder.
- 5 In witness whereof, I have hereunto affixed my signature, in the presence of two subscribing witnesses, this 23d day of May, 1913.
